UNITED STATES PATENT OFFICE

JAMES FRASER, OF EDGE MOOR, DELAWARE, ASSIGNOR TO SPEAKMAN COMPANY, OF WILMINGTON, DELAWARE, A CORPORATION OF DELAWARE

SHOWER HEAD

Application filed September 22, 1926. Serial No. 137,060.

The general object of my present invention is to provide an improved construction of shower head for use in lavatories, washrooms and other places. More specifically, it is my object to provide a shower head with simple, effective and readily cleanable strainer means.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of my invention.

Of the drawings:

Fig. 1 is an elevation in section of a preferred embodiment of my invention;

Fig. 2 is a sectional view on the line 2—2 of Fig. 1; and

Fig. 3 is an elevation in section with the needle head removed and the strainer partly removed.

In the drawings is shown a shower head including a hollow substantially shaped shower head casing A ordinarily made of cast metal, usually cast brass, and consisting of an elongated upper portion A' merging into a downwardly and outwardly tapering portion A² and a downwardly extending circumferential flange portion A³. The upper portion A' is substantially thicker than the lower portions and is threaded to receive the usual supply pipe connections (not shown).

Positioned in the chamber enclosed by the casing A and in threaded engagement with the lower part of the portion A' is a tubular conduit member B forming an extension of the supply pipe and having one end closed and formed with a threaded projecting bolt member B'. The pipe member B is provided with an outer circumferential flange B² adapted to contact with the bottom of the portion A' of the shower head A when the member B is in its extreme threaded position. The closed end of the supply pipe B is also provided with a similar projecting flange B³.

50 The tubular member B is provided with a

lateral water outlet opening, preferably in the form of two longitudinally extending lateral outlet openings B⁴ diametrically opposite and extending from near the base of the member B to the projecting flange B². 55

Surrounding the tubular member B is a strainer C in the form of a comparatively rigid tubular structure. In assembly the strainer C is slipped over the member B until its end portions contact with the centering flanges B² and B³, thereby advantageously leaving an annular space between the main body of the supply pipe member B and the strainer. The strainer is held in position thereon by a perforated face plate member D. In operation the strainer C is arranged to prevent foreign matter from passing from the outlet openings B⁴ in the supply pipe member B, and due to the annular space surrounding the supply pipe, a greater portion 65 of the strainer surface area will be in use than the immediate portion over the outlet openings. The shower head is therefore less liable to be rendered inoperative than if the strainer was in close contact with the supply pipe B. 70

The face plate member D is secured in position on the threaded projection B' of the conduit member B. The face plate member D preferably consists of a horizontal face plate D' having an upwardly extending vertical flange D² formed on the circumference thereof and a dish shaped flange D³ extending downwardly and outwardly therefrom. The face plate D' is provided with a multiplicity 80 of minute vertical passages D⁴ throughout the entire surface and an opening D⁵ at the center thereof. The vertical flange D² is arranged for sliding contact with the vertical flange A³ of the shower head casing A. The face plate member D is held in position by a clamping nut E on the projecting bolt member B'. 85

In order to prevent leakage between the various parts, rubber gaskets F' and F² are provided; the gasket F' being positioned between the lower end of the vertical flange A³ and the face plate D' and the gasket F² positioned about the projection B' and between 90 95 100

the closed end of the supply pipe member B and face plate D'.

In the assembly of the component parts of the shower head fixture the supply pipe member B is threaded into the vertical threaded portion A' of the shower head casing A until the flange B² engages with the lower part of the portion A'. The strainer C is then slipped on the member B, being centered by the flanges B² and B³, until it contacts with the lower part of the portion A'. The gaskets F' and F² are inserted into their proper positions and the face plate member D is adjusted on the projecting member B' with the vertical flange D² outside and in sliding engagement with the downwardly extending flange A³. The lock nut E is screwed on the bolt B', securing the parts in their proper positions. In use the shower head is threaded onto the water supply pipe connection (not shown).

In the normal use of the disclosed structure, the water passes from the supply pipe connection down through the supply pipe member B, passing out through the lateral openings B⁴ into the shower head casing chamber. The strainer C covering the openings B⁴ prevents any foreign matter from passing out to clog up the perforations in the face plate D'. The liquid is forced out of the shower head chamber through the multiplicity of vertical passages D⁴ and descends in the form of a spray.

The shower head shown and described is of simple and compact construction, especially easy to assemble and clean. The parts are so arranged that when the perforated face plate member D is removed as for cleaning, the tubular strainer will drop off by gravity, practically insuring that the strainer part C will be cleaned whenever the face plate D is removed. This is a desirable characteristic of the invention since a periodic cleaning of the strainer and face plate is essential for the maintenance of the best operating conditions, and frequently the cleaning and maintenance of a shower head is attended to by persons having little or no mechanical skill. The shower head construction is so simple that it may readily be assembled and taken apart by an unskilled worker. It is further evident that the parts requiring cleaning can be disconnected without disconnecting the shower head from the pipe supplying water to the shower head.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent is:

1. A shower head comprising a shell portion surrounding a chamber open at one side and a laterally ported supply pipe portion extending from said shell into said chamber toward its open side and having a bolt extension on the closed free end thereof, a perforated wall closing the otherwise open side of said chamber, a relatively rigid cylindrical strainer surrounding said pipe portion, said bolt extension extending through the perforated plate and an external clamping nut on said bolt extension. 70

2. A shower head comprising a shell portion surrounding a chamber open at one side and a supply pipe having a laterally ported body portion closed at its free end and extending from said shell into said chamber toward its open side, a perforated wall detachably secured to the free end of said pipe portion and closing the otherwise open side of said chamber, and a relatively rigid cylindrical strainer surrounding said pipe portion and of larger internal diameter than and spaced from the body of said ported pipe. 90

3. A shower head comprising a shell portion surrounding a chamber open at one side and a supply pipe having a laterally ported body portion extending from said shell into said chamber toward its open side, a perforated wall detachably secured to the free end of said pipe portion and closing the otherwise open side of said chamber, a relatively rigid cylindrical strainer surrounding said pipe portion and of larger internal diameter than the body of said ported pipe, and spaced centering flanges formed on said pipe, and said strainer contacting with the peripheral surfaces of said flanges, whereby an annular space is formed between said strainer and said body portion. 100

4. A shower head comprising a bell-shaped shell portion surrounding a chamber open at its under side, a liquid supply pipe having an elongated laterally ported portion closed at its lower end, said pipe extending from said shell into said chamber toward its open side, a tubular strainer surrounding and loosely contacting with said ported pipe portion, a perforated wall closing the otherwise open underside of said chamber, and means on the lower end of said pipe for holding said wall in position with said strainer resting thereon, whereby when said wall is removed, said strainer will separate from said pipe by gravity. 110

Signed at Wilmington, in the county of Newcastle, and State of Delaware, this 17th day of September, A. D. 1926. 125

JAMES FRASER.
